(57) **CLAIM**

The ornamental design of a snack tray, as shown and described.

DESCRIPTION

FIG. 1 is a top perspective view showing the front, right, and top sides of a snack tray in its environment;

FIG. 2 is a top perspective view showing the front, right, and top sides of the snack tray;

FIG. 3 is a right side elevation view of the snack tray;

FIG. 4 is a left side elevation view of the snack tray;

FIG. 5 is a front elevation view of the snack tray;

FIG. 6 is a rear elevation view of the snack tray;

FIG. 7 is a top plan view of the snack tray;

FIG. 8 is a bottom plan view of the snack tray; and,

FIG. 9 is a top perspective view showing the front, right, and top sides of the snack tray in an alternate orientation.

The broken lines in the drawings illustrate portions of the snack tray that form no part of the claimed design.
